UNITED STATES PATENT OFFICE.

DONALD M. BLISS, OF BATTLE CREEK, MICHIGAN, ASSIGNOR TO H. B. SHERMAN MANUFACTURING CO., OF BATTLE CREEK, MICHIGAN, A CORPORATION OF MICHIGAN.

STARTING SWITCH.

Application filed May 27, 1921. Serial No. 473,185.

To all whom it may concern:

Be it known that I, DONALD M. BLISS, citizen of the Dominion of Canada, residing at Battle Creek, in the county of Calhoun and 5 State of Michigan, have invented certain new and useful Improvements in Starting Switches; and I hereby declare that the following is a full, clear, and exact description thereof, reference being had to the accompanying drawings, which form part of 10 this specification.

This invention relates to so-called centrifugal switches which are adapted to be used in connection with rotatable members to be 15 automatically opened by centrifugal force after a predetermined speed of revolution has been reached. Such switches are commonly used in small alternating current motors of the single phase type and wherein 20 it is desirable to provide means for automatically opening the circuit through the auxiliary or starting winding when the motor has reached a predetermined speed.

The primary object of the invention is to 25 provide a simple switch of centrifugal type in which the sparking area is reduced to a minimum.

Another object is to provide a switch in 30 which the switch members will have a progressively separating action from the opposed contacts thus making successive make and break of the contact area as hereinafter explained.

Further objects are to provide a novel 35 form of switch members or blade and to provide means for lubrication between the rotating and fixed contact sections of the switch.

I will explain the invention with reference 40 to the accompanying drawings and summarize in the claims the novel features of construction and novel combinations of parts for which protection is desired.

In said drawings:

45 Fig. 1 is a diagrammatical view of a centrifugal switch embodying the present invention, showing the switch closed.

Fig. 2 is a like view of the switch shown in Fig. 1, showing the position assumed by 50 the switch blades after the motor is running but before it has attained full speed.

Fig. 3 is a similar view, showing the position of the contact blades after the motor has attained the predetermined speed.

Fig. 4 is a side view of one of the contact 55 blades partly broken away.

Fig. 5 is an end view of such blade.

Referring to Fig. 1, 1 and 2 designate the terminal leads or posts, and 3 and 4 are opposed contact segments of the motor opposed 60 to which are relatively movable contact blades 5 and 6 which are attached to the revolving rotor of the motor so as to be capable of movement in a radial direction away from contacts 3 and 4. As shown the contact blades 5 and 6 are retained on the rotor by means of pins or lugs 5^a, 6^a engaging slots in the blades; and the blades 5 and 6 are normally held in contact with the stationary contact segments 3 and 4 by means of helical contractile springs 7 and 8 connected to and between the adjacent ends of the contact blades 5 and 6 and normally holding the blades 5 and 6 in contact with the blades 3 and 4 until the motor has attained a predetermined speed sufficient to cause centrifugal force exerted upon the blades 5 and 6 to 70 overcome the resistance of the springs 7 and 8 and cause the blades to separate from the segments 3 and 4, thus breaking the circuit. 80 The segment 3 may be connected as usual by a conductor 11 to a starting winding 11^a and the latter to the terminal lead or post 1; the contact segment 4 may be connected by a conductor 12 with the terminal post 2, a 85 winding 12^a being interposed between the terminals 1 and 2.

In switches of this design, as ordinarily constructed (Fig. 1) the edge of the contact blades tends rapidly to wear the stationary 90 segments 3 and 4 both by reason of the extensive frictional contact between the two surfaces as well as from the sparking which takes place at various points around the circumference of the stationary segments when 95 the contact blades 5 and 6 finally break contact with the segments during rotation.

As stated the primary object of the invention is to prevent this undue wear and sparking. For this purpose I provide means 100 whereby the blades are caused to rock or tilt upon the segments in separating therefrom so that there is a gradual progressive lessening of the extent contact between the segments and the blades which contact is reduced to a small single point before the complete separation of the blades from the segments; this gradual separating action does 105

away with the objectionable and injurious 5
sparking and also does away with a great deal of the objectional frictional wear between the contact surfaces of the blades and 10
5 segments.

For this purpose the blades are preferably 15
hung so that their ends are unbalanced; and this may be accomplished by making one end 20
of each blade heavier than the other or less
susceptible to centrifugal force at one end
than at the other. A simple manner is to 25
make an opening adjacent one end of the
blade (as at 5^b and 6^b) as shown in Fig. 1,
rendering that end of the blade lighter than 30
the other, and thus renders the blade unbalanced.
As shown the perforated ends 13 and 14 of the blades (Figs. 1-3) are heavier than the ends 9 and 10 thereof. The springs 35
7 and 8 connecting the blades being of equal
strength it follows that when the speed of
rotation approaches the predetermined limit, 40
the heavier ends of the contact blades 14 and
13 will first separate from the stationary
segments without any spark whatever, the
lighter ends (9 and 10) of the blades are still 45
in contact with the stationary segments at
this instant (see Fig. 2).

As the speed increases still further, the 50
lighter ends 9 and 10 of the contact blades
will finally leave the stationary segments
thereby opening the circuit completely as 55
shown in Fig. 3.

When the current is shut off from the 60
motor and the rotor gradually comes to rest, the
lighter ends of the contact blades will be the
first to make contact with the segments and
finally the heavier ends 13 and 14 will rest on 65
the stationary segments. By reason of this
progressive action of the contact blades, the
arcing or burning of the contact blades is 70
confined to the light end section 9 and 10 of
the contact blades, and to a very small extent
of surface of the segments.

This progressive separating action of the 75
contact blades could be secured by using balanced
blades and making one of the springs
7 or 8 weaker than the other, therefore I do
not limit myself to the use of unbalanced
ends contact blades, but may use either or 80
50 both of these methods to secure the desired
progressive action.

Preferably the inner edge of each contact 85
blade is centrally notched, as at 5^c, 6^c to provide
a double contact surface for each blade.

As both the contact blades and the 90
stationary segments are usually composed of
similar metals of high conductivity, such as
brass, copper or bronze, and as it is not practicable
to lubricate the contacting surfaces 95
with oil heretofore there has been comparatively
rapid wear between the contacting surfaces
on account of mechanical friction as
well as sparking.

As stated one object of the invention is to 100
provide blades which will be practically self

lubricating. For this purpose each blade 105
is preferably made of two or more leaves
5^x, 6^x (see Figs. 4 and 5). The inner surfaces
of these leaves are roughened or grooved as
indicated at 5^y and such grooves are filled 110
with a lubricant such as graphite paste as
indicated at 5^z, and the leaves are then riveted
together with the layer of graphite between them.
As the graphite is not affected by heat it tends to distribute itself over the 115
contact surface of the blade and so provides
a practicable lubricant at the point of contact
with the segments.

The general design of a centrifugal switch 120
of this type with stationary segments and
revolving contact blades cooperating therewith
and connected by springs and actuated by
centrifugal force to open the circuit through
the starting winding at a predetermined 125
speed is not broadly new and no claim
is therefore made for such general design of
switch; but having the blades unbalanced so
as to have a progressive separating action as
above described for the purpose of reducing 130
the wear of the surfaces and limiting the
arcing to a predetermined section is novel; also
the particular construction of the unbalanced
blades is novel; and also making the
blades self lubricating as described is novel 135
and therefore what I claim is:

1. A centrifugal starting switch comprising 140
a stationary contact segment and a rotating
contact blade, and spring means engag- 145
ing the blade to hold it in yielding contact
with the contact segment but permitting
it to progressively separate from the
segment under the action of centrifugal
force.

2. In a centrifugal starting switch, the 150
combination of contact segments and relatively
rotating unbalanced contact blades co-operating 155
therewith whereby a progressive making
and breaking of the contact area between
the blades and segments is produced by the
action of centrifugal force, substantially as described.

3. In a centrifugal starting switch, the 160
combination of stationary contact segments,
unbalanced rotating contact blades cooper- 165
ating therewith, and spring means yield-
ingly holding the blades in contact with the
segments, whereby a progressive making
and breaking of the contact areas between
the rotating blades and segments is produced 170
by the action of centrifugal force, substantially
as described.

4. In a centrifugal starting switch, the 175
combination of stationary contact segments,
with unbalanced rotating contact blades co- 180
operating therewith to secure a progressive
make and break of the contact area of the
rotating blades as described.

5. In a centrifugal starting switch, the 185
combination of stationary contact segments
with unbalanced rotating contact blades co-

operating therewith and springs connecting the blades to hold them in yielding contact with the stationary segments whereby to secure a progressive make and break of the contact under the action of centrifugal force.

6. A centrifugal starting switch comprising stationary contact segments, rotating contact blades and springs yieldingly connecting the blades to hold them in yielding contact with the stationary segments, the contact being progressively broken at two predetermined contact points of each blade under the action of centrifugal force.

15 7. A centrifugal starting switch having one or more stationary contact segments and one or more unbalanced rotating contact blades cooperating therewith, and springs connecting the blades to hold them in yielding contact with the stationary segments, the blades rocking and partially opening the starting circuit at one speed, and fully opening the said circuit at a higher speed.

8. In a centrifugal starting switch, a contact member and a radially movable and slideable longitudinally unbalanced contact member cooperating therewith and rotatable relatively thereto, whereby a progressive making and breaking of the contact area between the members is produced by the rotating contact member tilting and separating progressively from the other contact member under the influence of centrifugal force as a predetermined speed is attained.

35 9. A centrifugal starting switch having a plurality of contact members, and a plu-

rality of radially movable and slideable longitudinally unbalanced contact members cooperating therewith and rotatable relatively thereto, whereby a progressive making and 40 breaking of the contact area between the members is produced by the rotating contact members tilting and separating progressively from the other contact members under the influence of centrifugal force as 45 a predetermined speed is attained.

10. In a centrifugal starting switch a contact member and a radially movable longitudinally unbalanced contact blade cooperating therewith comprising a plurality of 50 similar leaves and a lubricant between the leaves, said blade being rotatable relatively to the contact members; whereby a progressive making and breaking of the contact area between the blade and members is produced by the blade tilting and separating progressively from the contact member under the influence of centrifugal force as a 55 predetermined speed is attained.

11. In a centrifugal starting switch, the 60 combination of stationary contact segments with unbalanced rotating contact blades cooperating therewith to secure a progressive make and break of the contact area of the rotating blades as described, each contact 65 blade comprising a plurality of leaves and a heat resisting lubricant between the leaves, substantially as described.

In testimony that I claim the foregoing as my own, I affix my signature.

DONALD M. BLISS.
